(57) **CLAIM**

The ornamental design for the ambient temperature and humidity thermometer, as shown and described.

DESCRIPTION

FIG. 1 shows a perspective view of the front side of the thermometer.

FIG. 2 shows a front view of the thermometer.

FIG. 3 shows a back view of the thermometer.

FIG. 4 shows a left side view of the thermometer.

FIG. 5 shows a right side view of the thermometer.

FIG. 6 shows a top view of the thermometer; and,

FIG. 7 shows a bottom view of the thermometer.
